UNITED STATES PATENT OFFICE.

GEORGE E. BALL, OF TAUNTON, MASSACHUSETTS.

DESIGN FOR A BODY OF TEA OR COFFEE POTS OR SIMILAR ARTICLES.

No. 39,510.

Specification for Design.

Patented Sept. 8, 1908.

Application filed June 11, 1908. Serial No. 437,987. Term of patent 14 years.

To all whom it may concern:

Be it known that I, GEORGE E. BALL, a citizen of the United States, residing at Taunton, in the county of Bristol and Commonwealth of Massachusetts, have invented a new, original, and ornamental Design for the Body of a Tea or Coffee Pot or Similar Article, of which the following is a specification, reference being had to the accompanying drawing, forming a part thereof.

Figure 1 is a side elevation of the body of

a tea or coffee pot or similar article embodying my new design and Fig. 2 is a plan view thereof.

I claim—

The ornamental design for the body of a tea or coffee pot or similar article as shown.

GEORGE E. BALL.

In presence of—

GEORGE E. CHAMBERS,
HERBERT O. WOOLLEY.
